UNITED STATES PATENT OFFICE.

CHARLES EHRLICH, OF BROOKLYN, NEW YORK; MAX EHRLICH ADMINISTRATOR OF
SAID CHARLES EHRLICH, DECEASED.

WIRE FABRIC.

1,384,748.

Specification of Letters Patent. Patented July 19, 1921.

Application filed September 18, 1919. Serial No. 324,456.

To all whom it may concern:

Be it known that I, CHARLES EHRLICH, a citizen of the United States, residing in the borough of Brooklyn, county of Kings, city 5 and State of New York, have invented a new and useful Improvement in Wire Fabrics, of which the following is a specification.

This invention relates to a wire fabric for bed-springs, the purpose of the invention 10 being to provide a fabric which is made of a series of interlaced wire loops, each series of loops being made from a single piece of wire and each series being formed with intermediate or alternate resilient connecting 15 portions, so that the bedspring has lateral and diagonal resiliency, which is believed to be a new result with this particular type of bedspring.

The invention comprises essentially, a wire 20 fabric composed of a series of long narrow loops which run lengthwise of the bedspring, which are connected to each other by a series of loops which are adapted to be deformed or bent when strain is put upon them 25 laterally, so that the wire fabric which is obtained will stretch laterally. Longitudinal resiliency is imparted to the wire fabric by a series of helical springs attached to the respective long loops at the head and foot 30 of the bed, as is well known. It is also an important object of this invention to provide a bedspring which presents an unusually smooth upper surface, so that there is no tendency for the mattress or bedclothes to 35 catch in projections on the spring. This smoothness of the upper surface is of particular utility in that type of folding bed in which the bedspring is slideable in or out.

Other advantages of the invention will be 40 apparent from the drawings, illustrating several embodiments of the invention; and in which Figure 1 shows a section of the wire fabric as applied to a bed, Fig. 2 is an enlarged top view of a portion of the wire 45 fabric, Fig. 3 is a longitudinal section through the spring, and Figs. 4 and 5 are views of two modifications.

Referring to the drawings, in which similar reference characters indicate similar 50 parts, the wire fabric is composed of a plurality of long narrow U-shaped loops 1 formed by the two side portions 2 connected by the bight 3. The bight portion 3 is a simple bend and is integral with the side portions

2, and is bent downwardly out of the plane 55 of the portions 2, as is clearly indicated in Fig. 3. This bending of the bight 3 gives a spring which is very flat and smooth on both surfaces, and one that is of a minimum thickness, and is therefore particularly 60 adapted for springs for folding beds in which one spring slides relatively to another. Formed integral with the side portions 2 are a plurality of shorter, broader, 65 arcuate loops 4, the side portions 2 of the long loops being bent as indicated at 5 to form a neck portion, and again bent as indicated at 8, and at that point merging into the arcuate loops 4 on either side. The bight 3 engages in the bent portions 5 and 70 passes around and bears against the under side of the neck. The bends 5 and 8 and the loops 4 are all in the plane of the long loops. The wire forming the arcuate loops 4 need not be of the precise shape shown in 75 Fig. 2, but may be bent in other shapes out of a straight line connecting the points 5, 5.

One series of long loops is interlaced with respective long loops of another series by passing the bights 3 of one series of long 80 loops through the bights 3 of another series of long loops, from below; the several loops are then pulled away from one another until the respective bights 3 assume the position as shown in Fig. 2, that is to say, until the 85 bights 3 are seated in the bent portions 5, so that the sides 2 of one long loop are held in the bight of another long loop. The long loops 1 extend longitudinally of the spring, while the loops 4 have their greatest length 90 extending laterally of the spring. Longitudinal resiliency is imparted to the spring by a series of helical springs 6, connected 95 to the bights 3 of the last series of long loops, these springs 6 being attached to the head or foot of the bed indicated at 7. Lateral and diagonal resiliency is imparted to the spring by virtue of the intermediate connecting loops 4. It will be apparent that if 100 a lateral strain is put upon the spring, or if a diagonal strain is put upon the spring, that the loops 4 would tend to straighten out and that the bends at 5 and 8 would give and would tend to straighten out. How-

ever, inasmuch as the loops 4 and the bends 105 5 and 8 are all made of one piece of more or less resilient wire, the combined results of all these small deformations is to give a

high degree of diagonal and lateral resiliency to the complete bedspring which is formed of dozens of such loops.

- Referring to Fig. 3, in which the top of the spring is at the upper part of the figure, it should be noted that the spring is so assembled that there are no projecting portions on the top thereof. Due to the fact that the bends 5 and 8 and the loop 4 are all in the same plane as the long loops 1 a very flat type of spring is formed. These features are of particular utility in that type of folding bed in which one spring slides relatively to another and where, if there are any projecting portions, there is a tendency for one spring to catch in the other or for the spring to catch and tear the bedclothes.
- Referring to Fig. 4, a modification is shown in which the long loops 1 are connected to one another by an integral connecting portion 9 which may be bent into a plurality of similar bends or corrugations 10, the portion 9 being merged into the sides 2 through the medium of loops 5.
- This particular formation gives a structure which bends at loop 5 and bends in each of the small bent portions 10, when the spring is subjected to lateral or diagonal strains, so that the net result of the use of a large number of such bent portions is a spring having a high degree of lateral and diagonal resiliency.

Referring to Fig. 5, the modification there

shown is similar to the structure shown in Fig. 2, corresponding parts being similarly numbered. In this modification, however, the connecting loops 4 are made somewhat longer than in Fig. 2, to form a spring which has correspondingly greater lateral and diagonal resiliency. In this modification the loop 4 is between one-third and one-half of the length of long loop 1.

While I have illustrated several embodiments of my invention, it should be understood that it may be carried out in other ways, as defined within the scope of the attached claim.

I claim as my invention:

A wire fabric for a bedspring formed of a plurality of long loops, the side elements of the long loops being reversely bent at their lower ends in the plane of the long loops to form a neck, and being again bent outwardly in the plane of the long loops and forming a series of arcuate resilient loops intermediate the respective long loops, in the same plane with the long loops, the said side elements of the long loops being connected at their upper ends by an integral bight portion which is bent downwardly out of the plane of the long loops, said bight being a simple bend which engages against the underside of the neck portion of a long loop of another series.

Dated, Brooklyn, N. Y., Sept. 15, 1919.
CHARLES EHRLICH.
